DESIGN FOR A WRAPPING PAPER OR SIMILAR ARTICLE

Theodore L. Carter, St. Louis, Mo., assignor to Orchard Paper Company, St. Louis, Mo., a corporation of Missouri

Application April 3, 1940, Serial No. 91,445

Term of patent 7 years

To all whom it may concern:

Be it known that I, Theodore L. Carter, a citizen of the United States and a resident of the city of St. Louis, in the State of Missouri, have invented a new, original, and ornamental Design for a Wrapping Paper or Similar Article, of which the following is a specification, reference being had to the accompanying drawing, forming part thereof.

The figure is a plan view of a portion of a sheet of wrapping paper or similar article, showing my new design.

I claim:

The ornamental design for a wrapping paper or similar article, as shown.

THEODORE L. CARTER.
